UNITED STATES PATENT OFFICE

2,480,977

ROTARY CIGARETTE DISPENSER

Luis Süli, Buenos Aires, Argentina

Application September 7, 1945, Serial No. 614,851
In Argentina July 21, 1945

2 Claims. (Cl. 312—97.1)

1

My present invention refers to a novel combination application for smokers and card-players.

The main object of my invention consists in providing a novel and useful appliance which consists of the combination of a new type of cigarette box with an ash tray, a casing for playing-cards, and a counting frame for card-players.

Another object of my invention consists in providing a new type of cigarette box comprising a rotative cigarette holder, a cylindrical container for housing said cigarette holder, and a longitudinal slot provided in said container for taking out one by one the cigarettes from said holder.

Still another object of my invention consists in providing a new type of cigarette box comprising a rotative cigarette holder, a container formed by an outer cylinder and an inner cylinder for housing said cigarette holder, a longitudinal slot provided in each of said cylinders for taking out therethrough one by one the cigarettes from said holder.

Another object of my invention consists in providing a new type of cigarette box forming part of a combination appliance for smokers and comprising a rotative cigarette holder, a cylindrical container for housing said cigarette holder, said container having double walls coinciding longitudinal slots in said walls, and a cover fixedly connected to said cigarette holder for closing said container and for rotating said holder in said container.

My present invention combines the features of ingenuity with that of novelty, the first being represented by the ingenious combination in a homogeneous and compact assembly of all that is necessary for pleasantly passing the time by smoking and playing cards, whereas the feature of novelty is more particularly embodied in the construction and arrangement of the cigarette box which forms part of the combination appliance for smokers and card-players, according to my invention.

Besides the objects referred to, my present invention comprises the construction and arrangement of parts of the novel combination appliance as will be hereinafter more particularly described with reference to the accompanying drawing, on which:

Figure 1 is a plan view,

Figure 2 is a side elevation of the novel combination appliance for smokers and card-players according to the invention,

Figure 3 is a vertical section of the cigarette box forming part of the appliance shown in

2

Figures 1 and 2, said section being taken along the line III—III of Figure 4, and

Figure 4 is a horizontal section of the cigarette box along the line IV—IV of the Figure 2.

Referring to the accompanying drawing, showing by way of example only a practical embodiment of my present invention, the novel combination appliance for smokers and card-players comprises a base member 1 of suitable form and size, made of wood, metal, stone, plastic, or other suitable material, said base member being partly hollow so as to form an open cavity or space 2 destined for containing a pack of playing-cards (not shown).

15 The base member 1, near one of its ends, is provided at its upper surface with a cavity 3 of circular or any other desired form, constituting an ash tray, said cavity communicating with two or more flat open channels or grooves 4 adapted for depositing therein lighted cigars or cigarettes.

Upon the central portion of the base member 1 there are mounted a number of frames 5 made of metallic wire or other suitable material, each frame carrying a plurality of beads, balls or discs 20 6, thus forming counting frames which enable card-players to readily register the points of their game.

The base member 1 finally carries a cigarette box 7, which comprises an outer cylinder 13 and 30 an inner cylinder 12, both cylinders provided with coinciding vertical longitudinal slots 15 and 14, respectively, of sufficient width to permit a cigarette of normal size to pass therethrough.

The inner cylinder 12 contains a longitudinally grooved cigarette holder 8 constructed of any kind of sheet material in such a manner that its outer surface provides a plurality of adjacent grooves 9 adapted to form in combination with said inner cylinder 12 a plurality of substantially 40 confined longitudinal spaces of sufficient width and length to receive one cigarette of normal size in each of said spaces.

The cigarette box 7 is provided with a cover 10, which is fixedly mounted on the cigarette holder 8, the arrangement being such that, as said holder is loosely placed within the inner cylinder 12, without the edges 11 of the grooves 9 thereof being in contact with the surface of said inner cylinder, said holder may be readily 45 rotated by means of the cover 10 and thus the cigarettes contained in said grooves 9 may be moved around until they reach the slots 14, 15 of the two cylinders 12, 13 and may be taken out one by one through said slots.

50 The inner wall 12 of the cigarette box 7 may

be omitted, if desired, but conveniently the same is also rotatively disposed within the outer cylinder 13, and may be provided with a pair of pins or the like extending through corresponding horizontal slots provided in the wall of the outer cylinder 13, the arrangement being such that by means of said pins the inner cylinder 12 may be rotated relative the outer cylinder 13 over a short distance sufficient to move the slot 14 out of registration with the slot 15 and to thus close 10 the lateral opening of the cigarette box 7.

From the preceding specification and the disclosure of the accompanying drawing the novelty of combination and the utility of the combination appliance according to the invention will be readily appreciated, the same being not only useful and decorative for smoking tables in private homes, but may be also advantageously used in clubs, offices, etc.

It will be understood that the present invention is by no means restricted to the embodiment as described and shown, but that amendments and modifications as to form and details may be made therein as falling within the scope of the appended claims.

Having thus fully described the nature of my present invention, what I claim and desire to secure by Letters Patent is:

1. A cigarette holding arrangement comprising in combination an outer cylindrical container having a vertical axis; a longitudinal vertical slot in said outer cylindrical container extending parallel to said vertical axis thereof; an inner cylindrical container arranged within said outer cylindrical container coaxially therewith and being rotatable about said axis relative to said outer cylindrical container; a longitudinal vertical slot in said inner cylindrical container extending parallel to said vertical axis thereof; a cigarette holder rotatably mounted within said inner cylindrical container coaxially therewith; and a cover

for said holder and said containers fixedly mounted on said cigarette holder for rotating said cigarette holder within said inner cylindrical container.

- 5 2. A cigarette holding arrangement comprising in combination an outer cylindrical container having a vertical axis; a longitudinal vertical slot in said outer cylindrical container extending parallel to said vertical axis thereof; an inner cylindrical container arranged within said outer cylindrical container coaxially therewith and being rotatable about said axis relative to said outer cylindrical container; a longitudinal vertical slot in said inner cylindrical container extending parallel to said vertical axis thereof; a cigarette holder rotatably mounted within said inner cylindrical container coaxially therewith and comprising a cylindrical body provided on its outer surface with a plurality of longitudinal vertical ad- 15 jacent grooves forming a plurality of confined spaces between said holder and the inner surface of said inner cylindrical container; and a cover for said holder and said containers fixedly mounted on said cigarette holder for rotating 20 said cigarette holder within said inner cylindrical container.

LUIS SÜLI.
